N° 3106

Thomas Dolan Design for a Stocking Fabric

PATENTED
JUL 14 1868

Chas. H. Salmon
R. Williams

Thomas Dolan

United States Patent Office.

THOMAS DOLAN, OF PHILADELPHIA, PENNSYLVANIA.

Design No. 3,106, dated July 14, 1868.

DESIGN FOR A STOCKING-FABRIC.

The Schedule referred to in these Letters Patent and making part of the same.

TO ALL WHOM IT MAY CONCERN:

Be it known that I, THOMAS DOLAN, of the city and county of Philadelphia, State of Pennsylvania, have invented or produced a new and original Design for a Stocking-Fabric; and I do hereby declare that the accompanying drawing, and the following explanation thereof, form a full, clear, and exact description of the said design.

The figure in the drawing represents sufficient of the knitted fabric to illustrate the design.

In the body A of the fabric are parallel rows of diamond-shaped spots, *a*, and on each side of each row is a similar row of spots, *b*, arranged, in respect to those of the central row, as clearly illustrated in the drawing.

On each side of each pattern formed by these rows of spots *a* and *b*, is a zigzag line, *d*.

The spots *a* should differ in color or shade from the spots *b*, and both, as well as the zigzag line *d*, should differ in color or shade from the body of the fabric.

Without confining myself, however, to any specific color or shade—

I claim the design for a stocking-fabric, substantially as herein described, and represented in and by the accompanying drawing.

In testimony whereof, I have signed my name to this specification in the presence of two subscribing witnesses.

THOMAS DOLAN.
